UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed November 24, 1925. Serial No. 71,169.

The present invention relates to improvements in refrigerator cabinets and particularly to that type having a partition wall therein for dividing the cabinet into a plurality of compartments. Generally it has been the practice to provide a relatively thick insulating wall surrounding the partition in order to prevent condensation of moisture upon the walls of the food compartment.

One of the objects of the present invention is, in general, to improve the construction of a refrigerator cabinet.

More particularly it is an object to eliminate the relatively thick insulating wall between the cooling compartment and the food compartment.

Another object is to prevent water, which is condensed within the cabinet, from falling upon articles within the cabinet or upon the floor of the cabinet. One manner of accomplishing this object is to direct water, which condenses on the outer side of the partition wall of a cooling compartment, into a cooling compartment.

Other and further objects of the present invention will be apparent from the following description, reference being had to the accompanying drawings, wherein a preferred form of embodiment of the present invention is clearly shown.

In the drawings:

Fig. 1 is a fragmentary cross sectional view of the upper portion of a cabinet having an L-shaped food compartment, showing the side and bottom partition wall in elevation, the front partition wall being removed to show the interior of the cooling compartment.

Fig. 2 is a sectional view taken on line 2-2 of Fig. 1 also showing a sectional view of the front wall of the cooling compartment, and

Fig. 3 is a sectional view taken on line 3-3 of Fig. 2.

Referring to the drawings, there is shown a cabinet 20 which includes a rectangular shaped lining 21. The cabinet is divided into a food compartment 22 and a cooling compartment 23 by a side partition wall 24, bottom partition wall 25 and a front partition

wall 26. An evaporator cooling unit 28 is located within the cooling compartment 23 and comprises a header 29. The header 29 is clamped between the straps 30 and 31 and these straps are suspended by bolts 32. Bolts 32 are carried by U-shaped cross bars 33 which are carried by the frame of the cabinet. Evaporator 28 comprises a series of loops 35 which surround sleeves 36, which receive ice trays 37. The bottom partition wall 25 includes a sheet metal portion 38 formed integrally with the side partition wall 24. A thin layer of cork 39 is carried on the portion 38 and carries a pan 40. Aligned openings are provided in portion 38, cork 39, and pan 40 to provide a passage between the lower portion of the cooling compartment 23 and the food compartment 22. The pan 40 is provided with an upwardly extending flange 42 to prevent water accumulating in the pan 40 from passing through the opening 41. The portion 38 has an upwardly turned flange 43 for enclosing the edge of the insulation 39 adjacent the opening 41. A water shed 44 is located above the opening 41 and prevents water, which may drip from the evaporator, from falling through the opening 41. A drain 45 is connected with the pan 40 for conducting water from the cooling compartment.

The front wall partition 26 is secured to inwardly extending flanges 46 and 47 which are formed integrally with wall 24 and portion 39 respectively. An opening 48 in wall 26 provides access from the front of the cabinet to the ice trays 37. The lower portion of the front wall 26 is provided with two horizontal slits extending substantially across the entire width of the wall. The metal portion 49 between these slits is bent so that the upper end thereof extends outwardly and the lower end thereof extends inwardly to provide an opening 50 and the portion 49 providing an incline extending downwardly from the outside of the cooling compartment to within the cooling compartment. The side partition wall 24 is slit adjacent the lower end thereof and the portion 51 above this metal is bent inwardly thus providing an opening 52.

Water which condenses above the front wall 26 will move downwardly along said wall until it approaches the upper slit where it will fall on to the portion 49 through opening 50 to the interior of the cooling compartment. This water will then drop from the portion 49 to pan 40 in the bottom of the cooling compartment. Likewise water condensing on the side wall 24 will move downwardly and travel through opening 52 over the portion 51 and drop within the pan 40 and conducted out of the cooling compartment by the drain 45.

The partition walls 23, 25 and 26 form a unit which is suitably secured, as by screws 53, to the header clamping strap 31 and by screws 54 cooperating with downwardly extending flanges 55 formed integrally with portion 38. The partition wall 24 is provided with a cut-away portion 56 providing a passage for the circulation of air from the food compartment 22 to the cooling compartment 23.

With the type of construction shown in the present invention water condensing on the partition walls 24 and 26 will not drop upon the food stored within the food compartment or upon the floor of the food compartment.

The present invention therefore eliminates the use of an insulating wall around the partition defining the cooling compartment, thereby simplifying the construction and reducing the cost of manufacture of refrigerator cabinets.

While the form of embodiment of the present invention as herein disclosed, constitutes a preferred form, it is to be understood that other forms might be adopted, all coming within the scope of the claims which follow.

What is claimed is as follows:

1. A refrigerator cabinet comprising a substantially vertical wall, a substantially horizontal wall, said walls providing a cooling compartment within the cabinet, said vertical wall having an opening therethrough adjacent the horizontal wall and having an inwardly formed portion for directing the water of condensation from the outside of said wall into the cooling compartment.

2. A refrigerator cabinet comprising a sheet metal partition including a substantially vertical wall and a substantially horizontal wall, said walls providing a cooling compartment within the cabinet, said vertical wall being cut and bent to form an opening therethrough and to form a portion for directing the water of condensation from the outside of said wall into the cooling compartment.

3. A refrigerator cabinet comprising an integral partition having a substantially vertical portion and a substantially horizontal portion enclosing a cooling compart-

ment within the cabinet, said vertical portion having an opening adjacent the horizontal portion, and means integral with the partition and disposed out of the plane of the vertical portion for directing through said opening water condensed on the vertical portion.

In testimony whereof I hereto affix my signature.

JESSE G. KING.
